US00D598414S

(12) **United States Design Patent**
Joung et al.

(10) **Patent No.:** **US D598,414 S**
(b4) **Date of Patent:** **** Aug. 18, 2009**

(54) **CELLULAR PHONE**

(75) Inventors: **Joung Young Joung**, Seoul (KR); **Kyu Suh Park**, Seoul (KR); **Jin Wan Bae**, Seoul (KR); **Gang Ho Woo**, Seoul (KR)

(73) Assignee: **LG Electronics Inc.**, Seoul (KR)

(**) Term: **14 Years**

(21) Appl. No.: **29/324,600**

(22) Filed: **Sep. 16, 2008**

(30) **Foreign Application Priority Data**

Mar. 17, 2008 (KR) 30-2008-0011327

(51) **LOC (9) Cl.** **14-03**

(52) **U.S. Cl.** ..... **D14/138 G**

(58) **Field of Classification Search** ..... D14/138 R, D14/138 AD, 138 AC, 138 C, 138 G, 191, D14/203.1–203.8, 496, 138 AA, 138 AB, D14/137, 147, 218, 341–347, 247–248; D10/65, D10/78, 104; D13/168; D18/7; 455/566, 455/575.1, 575.3
